(57) **CLAIM**

What is claimed is a balloon with shot carrier, as shown and described.

DESCRIPTION

FIG. 1 is a front perspective view of the present invention.

FIG. 2 is a front perspective view of the present invention.

FIG. 3 is a side elevation view of the present invention.

FIG. 4 is a side elevation view of the present invention.

FIG. 5 is a side elevation view of the present invention.

FIG. 6 is a side elevation view of the present invention.

FIG. 7 is a top elevation view of the present invention; and,

FIG. 8 is a bottom elevation view of the present invention.

The broken line showing is for illustrative purposes only, and forms no part of the claimed design.
